UNITED STATES PATENT OFFICE.

EDWARD ROWSE, OF AUGUSTA, MAINE.

IMPROVED STEERING APPARATUS.

Specification forming part of Letters Patent No. **56,802**, dated July 31, 1866.

To all whom it may concern:

Be it known that I, EDWARD ROWSE, of Augusta, Kennebec county, State of Maine, have invented a new and useful Improvement in Steering Apparatus; and I do hereby declare that the following is a full, clear, and exact description thereof, which will enable others skilled in the art to make and use the same, reference being had to the accompanying drawings, forming part of this specification, in which—

Figure 1 is a vertical longitudinal section, and Fig. 2 is a top view, of my improvement in steering apparatus.

Similar letters of reference indicate corresponding parts.

This invention relates to certain improvements in that class of steering apparatus in which wheel-ropes or tackles are used in connection with a tiller and hand-wheel windlass, and whereby the wheel-ropes are kept taut at all parts of the stroke of the tiller, and the main objection to wheel-ropes or tackles thereby obviated, as hereinafter fully described.

A in the drawings represents the deck of a ship. B is the rudder-head, and b is the tiller. G is the steering-wheel, which has a barrel or windlass, E, and is supported at its front by a pedestal, h, and at its rear end by having a bearing in a stud, d, which is pivoted in the top of the rudder-head and rotates therein as the rudder-head turns. The end of the tiller is provided with a block having sheaves i i, Fig. 2, upon each side of the head of the tiller b. k k are pulley-blocks fixed to the deck A, and f f are the wheel-ropes. c is a rib which is fastened to the deck A, and in form represents a segment of a circle. The object of this segment or arc c c is to keep the "standing

parts" f f of the tackle or wheel-ropes always in the same position, so that the wheel-ropes f f do not become slack when the tiller is hard over to starboard or port, or as the tiller-head carries the parts more in and out of line with the securing-points m m k k on the deck. In this case the part f' of the tackle lies against the outside of the arc or rib c, and the said rib c holds the said part f' deflected at the same point always and obviates the greatly varying tension of wheel-ropes as ordinarily rigged and arranged.

As the tiller b vibrates in either direction one of the sheaves i picks the standing part f' of the tackle up off from the outer face of the rib c, while the opposite sheave i drops its standing part f upon the said outer face of rib c, and vice versa.

By these means the wheel-ropes are kept at a more uniform tension, and all tension and jerking motion of the tiller prevented, and the wheel-ropes are less liable to "ride" on the barrel E of the wheel.

The deflecting arc or rib c c is used with equal facility with the apparatus and tiller in the rear of the rudder-head B as when arranged in front of the same, as shown.

Having thus described my invention, what I claim as new, and desire to secure by Letters Patent, is—

The arrangement of the rib c, ropes f f, sheaves i i, tiller b, pulleys k, and rudder-head B, with its pivoted-stud d, operating, in combination with the windlass E, in the manner and for the purpose herein specified.

EDWARD ROWSE.
